W. P. KIDDER,
WATER VAPORIZER,
APPLICATION FILED APR. 5, 1919.

Patented Mar. 22, 1921.

Inventor,
Wellington P. Kidder,
By
A. Blenheim,
Attorney.

UNITED STATES PATENT OFFICE.

WELLINGTON P. KIDDER, OF BOSTON, MASSACHUSETTS.

WATER-VAPORIZER.

1,372,235.

Specification of Letters Patent. Patented Mar. 22, 1921.

Application filed April 5, 1919. Serial No. 288,410.

To all whom it may concern:

Be it known that I, WELLINGTON P. KIDDER, a citizen of the United States, and a resident of Boston, in the county of Suffolk and Commonwealth of Massachusetts, have invented certain new and useful Improvements in Water-Vaporizers, of which the following is a full, clear, and exact specification.

10 The object of this invention is the construction of an attachment whereby either watery vapor, or watery vapor mixed with air in any desired proportions, can at will be admitted to the carburetor or to the intake manifold.

20 My invention consists essentially of a water tank clamped to the exhaust manifold of an internal combustion engine, means for conveying the vapor therefrom to the intake manifold, and means controllable by the chauffeur for admitting different proportions of air to the vapor on its way to the intake manifold.

25 In the drawings forming part of this specification, Figure 1 is a side view of an attachment embodying my improvements. Fig. 2 is a detail sectional view of the air valve, looking from the opposite side.

30 Referring to Fig. 1, the reference character 1 designates a water tank designed to be snugly clamped against the exhaust manifold of the engine, 2 being the manifold and 3 the clamps or other attaching devices.

35 Preferably at the midlength of the tank 1 is a stand pipe 4 connected near its outer end with a tube 5 which communicates with the intake manifold 6, the stand pipe 4 terminating in a filling funnel 7. At the opposite side of the stand pipe from the end of 40 the pipe 5 is a boss 9 into which is screwed a threaded plug or valve 10 turned by a knurled hand piece 11 in convenient reach of the chauffeur. Thus valve 10 normally closes the air inlet 12, shown in Fig. 2, so 45 that by unscrewing the valve until the inlet 12 is internally exposed, air may be admitted from the atmosphere to the stand pipe 4.

50 The filling funnel 7 is closed ordinarily by a screw plug 13 actuated by a knurled thumb piece 15.

The operation of the device is as follows: The screw plug 13 having been unscrewed, water is poured through the funnel 7 until

the tank 1 is nearly filled, under conditions 55 of summer temperatures. During winter weather, the tank may be partially filled with water, allowing for ice expansion, without injury. Then the plug is screwed tightly into place, and the vaporizer permit- 60 ed to operate. As the water within the tank is heated by the exhaust within the manifold 2, vapor arises therefrom and es- 65 capes through the stand pipe 4 and pipe 5 into the intake manifold 6.

65 The hand piece 11 being in convenient reach of the driver, he can at will turn the same until a desired supply of air is admitted to the stand pipe or dome 4, and passes therefrom with the vapor to the in- 70 take manifold 6. A partial turn admits a slight amount of air; and a further turn, a larger amount of air, according as the chauffeur wishes a leaner mixture for the engine, or otherwise.

75 The chief advantages of this device are its extreme simplicity in construction and economy of manufacture. It is automatically operative at all times. Can be immediately adjusted to admit air with the vapor 80 in any desired proportion. The vapor dome is made the filling device. The entire vaporizer is readily attached to any engine, no matter of what make.

85 What I claim is:

The combination with an internal combustion engine having an intake manifold, of a closed water container, means for heating the same, a member rising from the container having a vertical passage through it 90 into the container, the upper end of said passage being laterally enlarged to form a funnel, a screw plug for removably closing said upper end, a cross passage being formed in said member communicating with said 95 vertical passage, one end of said cross passage being connected with said manifold, the other terminal portion of said cross passage having an air inlet laterally therein, and a screw plug screwing into said termi- 100 nal portion to adjustably vary the air inlet, and having means in the reach of the chauffeur for turning said screw plug.

In testimony that I claim the foregoing invention, I have hereunto set my hand this 105 31st day of March, 1919.

WELLINGTON P. KIDDER.
